(57) **CLAIM**

The ornamental design for a T-shaped light fixture, as shown and described.

DESCRIPTION

FIG. 1 is top, right facing perspective view of our new design for an T-shaped light fixture;

FIG. 2 is a bottom, right facing perspective view thereof;

FIG. 3 is an elevated facing view thereof;

FIG. 4 is an elevated rear view thereof;

FIG. 5 is a top, plan view thereof;

FIG. 6 is a bottom, plan view thereof;

FIG. 7 is an elevated right side view thereof; and,

FIG. 8 is an elevated left side view thereof.

In the drawings, the broken lines show portions of a

T-shaped light fixture that form no part of the claim.

The T-shaped light fixture is shown with a symbolic break in its height. The appearance of any portion of the article between the break lines forms no part of the claimed design.
